(57) **CLAIM**

The ornamental design for a reference array, as shown and described.

DESCRIPTION

FIG. 1 is a perspective view of a reference array showing our new design.

FIG. 2 is a front view thereof.

FIG. 3 is a rear view thereof; and,

FIG. 4 is a left side view thereof.

The broken lines immediately adjacent the shaded areas represent the bounds of the claim, while all other broken lines are directed to environment and are for illustrative purposes only; the broken lines form no part of the claimed design.

1 Claim, 4 Drawing Sheets

FIG. 1

FIG. 2

FIG. 3

FIG. 4
